UNITED STATES PATENT OFFICE

LAWRENCE B. WEBSTER, OF MARION, INDIANA

DESIGN FOR A JAR OR SIMILAR CONTAINER

Application filed December 3, 1931. Serial No. 41,959. Term of patent 3½ years.

To all whom it may concern:

Be it known that I, LAWRENCE B. WEBSTER, a citizen of the United States, residing at Marion, in the county of Grant and State of Indiana, have invented a new, original, and ornamental Design for a Jar or Similar Container, of which the following is a specification, reference being had to the accompanying drawings, forming part thereof.

Figure 1 shows the front view and Figure 2 shows the side view of an ornamental jar or similar container, showing my new design.

I claim:

The ornamental design for a jar or similar container, substantially as shown.

LAWRENCE B. WEBSTER.
